United States Patent Office.

JACOB CORNWELL, OF KALAMAZOO, MICHIGAN.

Letters Patent No. 70,806, dated November 12, 1867.

IMPROVED SILENT BOLT-FEEDER.

The Schedule referred to in these Letters Patent and making part of the same.

TO ALL WHOM IT MAY CONCERN:

Be it known that I, JACOB CORNWELL, of Kalamazoo, in the State of Michigan, have invented certain new and useful improvements in Silent Bolt-Feeders; and I hereby declare that the following is a full, true, and exact description of the same, reference being had to the accompanying drawings, and to the letters of reference marked thereon. In the drawings annexed, which make a part of this specification—

Figure 1 represents a side elevation of my feeder.

Figure 2 is a vertical section of the same taken through the centre.

The letter A designates the frame of my machine, which is strengthened by the cap-pieces b and tier C. D represents a hoop made of any suitable material, the said hoop resting on the sill E, and supported at its opposite sides by the cap-pieces b. F designates a spindle, with its lower end resting on the foot-block g, and extending upwards at the centre of hoop D to about two-thirds of the height of D. m and n are two circular platforms, through the centre of which the spindle F passes, the said platforms being keyed to F, so as to partake of its motion. The lower platform m is bolted to the arm f, which, with the motion of spindle F, will play on the bottom of hoop D. The arm f is designed, as it revolves, to scrape the flour from the bottom of hoop D, and conduct it to the mouth of the spout i. H represents another hoop placed inside of hoop D. Between the hoops H and D there will be space of an inch, more or less, to admit of a free circulation of air. The hoop H is formed with a flange at top, which is fastened to the circular opening in top G. Embracing the hoop H is a forked lever, (see fig. 3,) the tines of which are made to embrace the hoop H at opposite points, midway of the circumference of H, the ends of said tines being allowed to play in loops on the side of hoop s. The object of lever L is to regulate the quantity of flour that passes from the platforms m and n into the spout i, which carries the flour to the bolt. Motion is given to the platforms m and n by bevel-wheel h, on spindle F, the said bevel-wheel being geared into driving-wheel k.

The object of my invention is to spread out the flour as soon as it is received from between the millstones, and ventilate it before it enters into the bolt. By this operation the clogging of the bolt will be prevented.

Having thus described my invention, what I claim, and desire to secure by Letters Patent, is—

1. The revolving platform m, provided with scraper f, in combination with the revolving platform n, substantially in the manner set forth.
2. In combination with the subject-matter of the above, I claim lever L and band s, substantially as described.

In testimony that I claim the above I set my signature in presence of two witnesses.
